GRAIN DISTRIBUTOR

Roy I. Patterson, Golden Valley, Minn.

Application April 21, 1943, Serial No. 483,969

20 Claims.

(Cl. 193—31)

My invention relates to grain distributors and has for its object to provide a compact and exceptionally efficient apparatus which will receive grain from an elevating leg in a grain elevator and is adapted to discharge the grain to any of the bins in the grain elevator.

In the handling of grain, particularly in the country elevators of the smaller type, it is customary to dump the grain from trucks or wagons by which it is hauled to the elevator, into a receiving hopper from which it is elevated by means of a series of buckets secured to an endless belt or endless chains and which run over a head pulley, the grain being dumped from the head pulley into a hopper from which leads a delivery spout. From this spout the grain has to be chuted to any one of a very considerable number of bins located in the elevator. Heretofore there has been a problem both as to getting the grain chuted to the various bins and as to preventing escape of dust which might become oxidized and form a dangerous explosive. In general, by former practice an elevator has had to lose the equivalent of one story in height in order to get the necessary lengths of delivery chutes to reach all of the bins. Also, there has been insufficient protection against escape of dust.

I have discovered that all of these difficulties may be obviated and an unusually compact, efficient and economical distributing means be provided by arranging a vertical casing having one or more vertical passages therein, said passages being closed on all sides except for openings leading to the chutes which are located along both the open side and the side of the casing opposite thereto, together with a slidable duct mounted within the casing and carrying means for directing material therefrom into a selected one of the distributor chutes. This duct will have three of its sides permanently closed with one side open except for a belt secured thereto which, to the extent which the slidable duct is lowered or raised forms a fourth wall extending downwardly from the point of inlet of the grain. The slidable duct is open at its bottom, but is provided with a swinging gate which may form a sloping bottom closure cooperating with the chute passageways whereby the duct may be put in communication with any of the grain carrying chutes.

Means is provided for lifting and lowering the slidable duct by means of the aforesaid closure belt and for shifting the bottom closure to cause it to communicate with a selected duct on one or the other sides of the distributor.

In all positions of the sliding duct the passageway from the discharge from the elevator leg is closed to the point of junction with one of the distributor chutes, thus effectively preventing the escape of dust therefrom.

The invention lends itself particularly to the

use of two or more inlets from discharge spouts of multiple elevating legs, each of which is sealed into the inside of the slidable ducts. In the present invention I have shown two such distributor chambers and it will be obvious that one or more than two can be employed.

It is therefore the object of my invention to provide in combination with distributor ducts extending downwardly in an angular direction from opposite sides of a frame passageway, a slidable duct mounted to move vertically in said main distributor chamber with means connected to any of the delivery ducts and means to shift that connection at will.

15 The full objects and advantages of my invention will appear in detail in the specification hereinafter given, and the novel features of the invention by means of which the above-noted advantageous results are secured will be particularly pointed out in the claims.

20 In the drawings illustrating an application of my invention:

Fig. 1 is an end elevation view of the plant in operative position, showing the take-off ducts, the lead-in from the elevator leg, and the belt operating pulleys and cords.

25 Fig. 2 is a part perspective side elevation of the plant, showing the manner in which the take-off ducts are disposed relative to one another.

30 Fig. 3 is a sectional plan view taken on line 3—3 of Fig. 2.

Fig. 4 is an end elevation view of the top of the construction, showing the manner in which the slidable chute is counterweighted.

35 Fig. 5 illustrates the end of the spout from the elevator leg and the means of removably sealing it into the appliance.

Fig. 6 is an enlarged transverse sectional view taken on line 6—6 of Fig. 1.

40 Fig. 7 is an enlarged fragmentary side elevation view of the lower end of the vertically slidable duct or chute showing its relation to the outlets on opposite sides.

45 Fig. 8 is a longitudinal sectional view of the lower end of the slidable chute.

Fig. 9 is a sectional view taken on line 9—9 of Fig. 8.

Fig. 10 is a perspective view of one of the spout connectors attached to the distributor body.

50 Fig. 11 is a front view of a spout connector of symmetrical form, showing a conical direct connection end.

Fig. 12 shows a different form of spout connector.

55 Fig. 13 is a sectional view taken on line 13—13 of Fig. 12.

A framework is provided which as shown in Figs. 1, 3 and 6, comprises sets of uprights 15, 17 and 19 on one side, and uprights 16, 18 and 60 20 on the opposite side. These respective sets of

uprights extend vertically between common lateral planes as well shown in Fig. 6, and may be composed of any suitable material, such for example, as two-by-four lumber. A second set of uprights 21 and 23 on one side, and 22 and 24 on the other side, are positioned inside of the respective uprights 15 and 19 and 16 and 20 as clearly shown in Fig. 6. The uprights 21 and 23 will be rested upon a floor stringer 25 and the uprights 22 and 24 will be rested upon a floor stringer 26. Upon the outer edges of the uprights 15 and 16 is secured a cover 27 which may be formed of any suitable material, such for example, as boards, but which will have removable portions 28, 29, Fig. 2, which will permit access into the space 30 outlined by the several uprights. Similarly a cover 31 having similar removable members is attached to uprights 19 and 20 enclosing a space 32 to which the removable members will open. Bearing strips 33 of suitable material, such as some smooth metal, are applied to the inside faces of the uprights 21, 22, 23 and 24, as clearly shown in Fig. 6. Similar bearing strips 34 and 35 are applied to one set of edges of uprights 18 and 17, respectively, and other similar bearing strips 36 and 37 are applied to the opposite edges of uprights 18 and 17. There are thus formed two rectangles of vertical bearing strips 33, 34, 35, and 36, 37, respectively, which outline spaces or channels 38 and 39 within the vertical limits of the uprights forming the frame structure above-defined.

Extending fully across the sides of said spaces 38 and 39 and secured by angle irons 40 fast on the edges of the transversely positioned uprights 21, 22, 23 and 24, are sets of spout connectors 41a and 41b at one side, and 42a and 42b at the other side as best shown in Fig. 1. These are called here spout shoes.

These spout connectors are shown in detail in Fig. 10. Each of them comprises a top wall 43 and parallel bottom wall 44 (indicated in dotted lines); a back side wall 45 (indicated in dotted lines) and a front side wall 46. As indicated at 47, Fig. 10, the inner expanded end of all of these members 41a, 41b, 42a and 42b, is entirely open and faces the open sides of the spaces 38 and 39, extending across these spaces and across the central uprights 17 and 18.

The wall 46 has a bend, as indicated at 48, which in conjunction with the back wall 45 provides a narrowed laterally turned extension 49. The members 41a and 42a are, of course, similar and each has the laterally turned extension 49, all as clearly shown in Fig. 2. The spout connectors 41b and 42b correspond in their structural arrangement with the members 41a and 42a except that they have extensions 50 which are angularly turned in the opposite direction, all as clearly shown in Fig. 1. The extensions 49 and 50 are provided with semiconical adapters 51 which are adapted to be united with round pipes each going to a separate bin. The edges of the opening 47 are such that when the parts are held in position they slope downwardly as clearly shown in Figs. 1, 2 and 7. These parts are secured to the uprights 21, 23 and 22, 24, by means of the short angle pieces 40 above referred to, and which are clearly shown in Fig. 2.

With the construction above defined, the spaces or channels 38 and 39 open at their ends into spaces 30 and 32 which are otherwise enclosed and open at their sides into the openings 47 leading into the spout connectors 41a, 41b, 42a, and 42b.

Obviously, if it be so desired, only one channel such as 38 or 39 might be provided, or more than two such channels. In either case the principle of operation of the structure would be the same. Also, the particular dimensions of this or these channels formed within the framework and the dimensions of the spout connectors may be varied as desired to meet requirements.

10 In each of these spaces or channels is a chute slide designated generally as 52 for space 39 and 53 for space 38. Since these two chute slides are identical in construction, the description for each will be the same with the same reference numerals. Referring particularly to Figs. 6, 7, and 8, each chute slide 52 and 53 comprises a pair of side plates 54 and 55 which are normally held in engagement with the outer bearing strips 33 and the inner bearing strips 36, 37 and 34, 35, respectively. A back plate 56 in each case is secured along its side edges at 57 and 58 to the two side plates but spaced inwardly at their edges as indicated at 59. At their bottoms the side pieces 54 and 55 are held together by a bottom transverse plate 60, Fig. 8, and are provided with a pair of inside reinforcing members 61 and 62.

30 The bottoms of the side pieces 54 and 55 are cut away so that angular edges 63 and 64 form an upwardly-turned open V, see Figs. 7 and 8. This V is also formed in the reinforcing plates 61 and 62. At about the point of the V, ears 65 and 66 (the latter shown in dotted lines in Fig. 8) are secured to these plates and have journaled therein at the V a transverse shaft 67 shown in dotted lines in Fig. 6. Fast on the shaft 67 is an oscillatable bottom guide plate comprising a central member 68 and side members 69, 70, which plate is adapted to be positioned so as to close the lower end of the chute slide 52 (or the chute slide 53 accomplishing the latter in the same manner). This closure is effected as clearly indicated in Fig. 8 by engagement of the side edges of the oscillatable plate with the side walls of the reinforcing plate 61 and below the shaft 67 with one or the other of the oblique edges 63 or 64 of the reinforcing plates 61. The upper end 71 of the oscillatable plate engages the transverse plate 60 adjacent an abutment 72 fast on said plate, and the end 71 of the oscillatable plate in its other position may engage the back plate 56 adjacent or in contact with abutment 73. The lower end 74 of the oscillatable plate extends below the lowermost portion of the side plate 56, all as clearly shown in Fig. 8.

60 To oscillate the plate from the position shown in Fig. 8, to the opposite position, a bar 75 indicated partially in dotted lines in Fig. 8, is fast on the end of the shaft 67 protruding into the space 30, Fig. 6, beside the respective chute slide 52. To this bar is secured a cord 77 which extends downwardly over a pulley 78, Fig. 1, and outwardly to any suitable stand where the same may be pulled and tied by an operator to shift the oscillatable plate from the position of Fig. 8 to the position where it extends in the opposite oblique direction. A second cord 79 attaches to the bar 75 and runs upwardly over a pulley 80, Fig. 1, and extends to the operator's station where it may be drawn and fastened to oscillate the plate back to the position of Fig. 8.

70 By these means the oscillatable plate may be shifted to either of two positions to cause the grain coming down the sliding chute to pass

either to spout shoes 41a, 41b, on one side, or 42a, 42b on the opposite side. The back plate 56 is cut away at 81 and the transverse securing plate 60 is likewise cut away at 82, leaving an opening there for grain to move either to right or left into the spout shoes 41a, 41b or 42a, 42b.

By observing Fig. 7 it will be noted that the oscillatable plate is positioned extending into and engaging with the lower end portion 74 and the bottom wall 83 of the lowermost spout 42a. This is typical of the form of engagement of the oscillatable plate with any of the spout shoes. The shift from the position shown in Fig. 7, where the engagement is with the lowermost spout 42a, to similar engagement with the lowermost spout 41a, is effected by lifting the slide until the bottom edge of the extension 74 of the oscillatable member will pass the edge 84 of spout shoe 42a and likewise pass the similar edge 85 of the other spout shoe member 41a. Then when the slide is dropped, the engagement of the end portion 74 of the oscillatable member with the wall of a spout shoe will hold the slide in the position for discharging grain to whichever one of the spout shoes 41a, 42b, or 42a, 42b, has been selected to receive the grain from the elevator legs.

To raise or lower the chute slide a belt 86 is secured by bolts 87, Fig. 8, to the transverse plate 60. This belt is provided with reinforcing strips 88 and 89 at its sides which hold the belt at its edges in engagement with the side walls 54 and 55 of the chute slide. This belt 86 passes over a roller 90, Fig. 3, at the top of the frame. To the ends of the belt are secured cords 91 and 92 which may be carried to any desired point where a pulley, either operated by hand or other means, may furnish the power to raise the chute slides. By this means the chute slide can be brought into position so that the oscillating member 68 may be caused to engage any of the spout shoes 41a, 41b, or 42a, 42b. To make easier the lifting of the chute slide, a counterweight 93 is secured to a cord 94 which passes over a high pulley 95, the cord 94 being attached at 96 to a connector iron 97 secured to the chute slide.

The spouts 98 and 99 for delivering the grain from the elevating legs to the distributor, are indicated in dotted lines, in Fig. 2. The form of these spouts is best shown in Figs. 3 and 5. The outlet of the spout will be preferably rectangular as indicated at 100 in Figs. 2 and 3. A packing strip 101 will surround the outside of the spout section to engage and wipe the walls of the chute slide 72 (or 73), and also to engage the belt 86 whereby the delivery of grain will at all times be substantially sealed into the chamber within the chute slide and the escape of dust effectively prevented.

As shown in Fig. 7, a self-closing door 102 is provided in the side walls 54 and 55 and opens into the spaces 30 and 32. This door has two functions. When either of the removable portions 28 or 30 are withdrawn, the door 102 may be pulled open to permit inspection or entrance into the chute slide for any desired purpose. More important, when grain is being fed through the chute slide and for any reason the same becomes clogged and grain builds up in it, such as not infrequently happens because the bin to which the grain is being delivered becomes full, the self-closing door 102 may yield, opening into the space 30 (or the space 32). This space is in effect a chute which will be carried through the floor and connected with an extension chute 116 which leads to the dump pit where the elevator picks up

the grain. The result would be simply to cause the grain to circulate back until the operator discovers that the bin is full and the chute clogged. This discovery ordinarily will take place as soon as the door 102 is forced open and the grain begins to rattle down through the extension chute 116, as it will make a noise quite different from that which ensues while the grain is being fed to a chute leading to a bin.

10 In Figs. 11, 12, and 13, a variant form of the spout shoe is shown wherein a straight-sided symmetrical funnel 103 extends into a cylindrical outlet spout 104 and that in turn to a portion 105 as shown in Fig. 11, which latter will form a connector with the spout at various angles, or an elongation of the part 104 may be as indicated at 106 and may have telescoped therewith a second portion 107 which is held in position by a bead or rim 108 and a securing device 109 fast on the cylindrical extension 106. The conical portion 105 to whatever form of extension 104 it may be attached, is adapted to enter a similar enlarged semiconical section 110 which may be secured by a pivot arrangement 111 to the conical member 105 and thus make adjustment as desired for connection with any selected spout.

Although under normal operative conditions the weight of the chute slide 52 (or 53) is amply sufficient to drop it to any desired position when the belt 86 is released for that purpose, there may be conditions such that the slide chute might have a tendency to stick. In order to take care of such a situation I connect a pull cord 112 at 113 to the framework and carry it over a roller 114 on the chute slide, the position of these parts being indicated in dotted lines in Fig. 1. The cord 112 is also carried under a roller 115 on the frame. It follows that by pulling on cord 112, force will be applied to the chute slide through roller 114 and the sticking of the chute slide, if and when it occurs, will be readily overcome.

The advantages of my invention will be apparent from the foregoing description. By an exceedingly compact and simple arrangement of parts, a framework constructed of ordinary lumber and occupying very little room, both laterally and particularly in elevation, the discharge from the elevator legs may be simply and effectively connected to any of the spouts for distributing the grain to any number of grain bins in an elevator. There are no complicated parts to get out of order, and adjustment from one spout shoe to another may be effected speedily, easily and certainly. The distribution, while adapted for very numerous different connections and for handling large volumes of grain, is non-the-less relatively moderate in cost.

In the specification and claims presented here-with reference has been made generally to the handling of grain. It will be understood, however, that the invention is applicable to the handling of any kind of granular material such for example as ground grain, feed, flour or the like, and other ground or granular material such as 65 Portland cement. The invention has to do with the distribution of any kind of material adapted to flow by gravity. It is also applicable to such material when it is delivered from other means than an elevator leg such for example as where it is delivered by being blown.

I claim:

1. In combination with the discharge spout of a grain elevator leg, a grain distributor comprising a framework forming a vertical open-walled channel leading to said discharge leg, a multi-

plicity of spout shoes opening into said channel, and a vertically movable chute slide cooperating directly with said discharge leg for receiving and controlling the flow of the grain therefrom, said chute slide having a bottom movable in said channel and adapted to cooperate with a selected one only of said spout shoes and to control the flow of grain delivered through this chute slide to go to said selected spout shoe only.

2. In combination with the discharge spout of a grain elevator leg, a grain distributor comprising a framework forming a vertical open-walled channel leading to said discharge leg, a multiplicity of spout shoes opening into said channel, a vertically movable chute slide cooperating directly with said discharge leg for receiving and controlling the flow of the grain therefrom, said chute slide having a bottom movable in said channel and adapted to cooperate with a selected one only of said spout shoes and to control the flow of grain delivered through this chute slide to go to said selected spout shoe only, and means for moving said chute slide up and down along said channel to bring said bottom into cooperation with any selected spout shoe.

3. In combination with the discharge spout of a grain elevator leg, a grain distributor comprising a framework forming a vertical channel leading to said discharge leg, a multiplicity of spout shoes opening into said channel, a vertical chute slide cooperating with said discharge leg for receiving the grain therefrom, said chute slide having a bottom adapted to cooperate with a selected one only of said spout shoes and to control the flow of grain delivered through this chute slide to go to said selected spout shoe only, and a belt adapted to form a closure to one side of the chute slide connected to the bottom thereof for moving it up and down, to bring said bottom into position to cooperate with a selected spout shoe.

4. In combination with a discharge spout of a grain elevator leg, a grain distributor comprising a framework forming a vertical channel into which said discharge spout projects, a multiplicity of spout shoes opening into said channel, and a vertical chute slide having an open side through which said discharge spout projects, said chute slide having a bottom adapted to cooperate with a selected one only of said spout shoes to control the flow of grain from the discharge spout through the chute slide to go to said selected spout shoe.

5. In combination with a discharge spout of a grain elevator leg, a grain distributor comprising a framework forming a vertical channel into which said discharge spout projects, a multiplicity of spout shoes opening into said channel, a vertical chute slide having an open side through which said discharge spout projects, said chute slide having a bottom adapted to cooperate with a selected one only of said spout shoes to control the flow of grain from the discharge spout through the chute slide to go to said selected spout shoe, and a belt connected with the lower part of said chute slide and operating to close the open side of said chute slide up to the entrance therein of the discharge spout for moving the chute slide up and down to bring said bottom into position to cooperate with the selected spout shoe.

6. In combination with the discharge spout of a grain elevator leg, a grain distributor comprising a framework forming a vertical channel leading to said discharge leg, two sets of spout

shoes opening into said channel on respective opposite sides thereof, each set comprising a multiplicity of said spout shoes, and a vertical chute slide cooperating with said discharge leg for receiving the grain therefrom, said chute slide having a bottom adapted to cooperate with a selected one only of said spout shoes and to control the grain delivered through the chute slide to go to said selected spout shoe only, said bottom being pivotally mounted and having means for oscillating it on said pivot to cause it to cooperate with the spout shoes of either set.

7. In combination with a discharge spout of a grain elevator leg, said spout formed with a rectangular rim having sealing gaskets on the outside thereof, a grain distributor embodying a multiplicity of spout connections and a vertical chute slide having means for moving it vertically to cause it to cooperate with any of said spout connections, said chute slide being rectangular in cross section and having an open side through which said discharge spout projects, the gaskets of said discharge spout engaging the inner walls of the chute slide to seal the same against the escape of dust.

8. In combination with a discharge spout of a grain elevator leg, said spout having a rectangular rim having sealing gaskets on the outside thereof, a grain distributor embodying a multiplicity of openings for spout connections arranged in vertical order, a vertical chute slide rectangular in cross section and having an open side through which the discharge spout projects, and a belt connected to the lower part of the chute slide for moving it vertically and operating to close the open side below the discharge spout, the gaskets of said discharge spout engaging the inner walls of the chute slide and the upper inner surface of the belt to seal the interior of the chute slide against the escape of dust.

9. In combination with a discharge spout of a grain elevator leg, a grain distributor embodying a multiplicity of laterally extended openings to the spout connections arranged in vertical order one above the other, a vertical chute slide cooperating with said discharge spout, means to move the slide vertically along said openings, a pivoted bottom carried at the lower end of said chute slide, and being of a length to extend outside the limits thereof, an opening formed in the side of the said chute slide across the open lower limit of which said extended bottom may be swung, and means to swing the chute slide on its pivot to bring the extended end into contact with the bottom of a selected one of said spout connectors so that grain delivered through said chute slide will go only into said selected spout connector.

10. In combination with a discharge spout of a grain elevator leg, a grain distributor embodying two sets of laterally extended openings to spout connectors each set arranged in vertical order one above the other and spaced apart so as to face each other, a movable chute slide between said sets of openings cooperating with said discharge spout, means for moving the slide vertically between said openings, a pivoted bottom carried by the lower end of said chute slide and being of a length to extend outside the limits thereof, openings formed in opposite sides of said chute slide across the open lower limit of either of which said extended bottom may be swung, means to swing the chute slide on its pivot to bring the extended end into contact with

the bottom of a selected one of either of said sets of spout connectors so that grain delivered through said chute slide will go only into said selected spout connector.

11. In combination with a discharge spout of a grain elevator leg, a grain distributor embodying opposed sets of laterally extended openings to spout connectors said sets of openings being respectively arranged in vertical order one above the other and spaced apart so as to face each other, means cooperating with said discharge spout for producing an extensible chute closed except at its sides adjacent its bottom to conduct grain from the discharge spout to any selected one of said openings, and means at the bottom for closing said extensible chute to cause the grain passing through it to enter the selected one of the spout connector openings.

12. In a grain distributor having a framework forming a vertical channel, a series of spout shoes secured to said framework along the side thereof, one above the other, each shoe having a laterally extended opening from said channel into and across the width of said channel, and each shoe having a spout connector extension angularly disposed laterally with respect to the vertical extent of the channel, the angles of said extension being alternately in opposite directions for the several shoes.

13. In a grain distributor having a framework forming a pair of adjacent vertical channels, a spout shoe secured to said framework having a laterally extended opening from said channels into and across the widths of both said channels, and having a spout connector extension angularly disposed laterally with respect to the vertical extent of the channel.

14. In a grain distributor having a framework forming a pair of adjacent vertical channels, a series of spout shoes secured to said framework along the side thereof, one above the other, each shoe having a laterally extended opening from said channels into and across the widths of both said channels, and each shoe having a single spout connector extension angularly disposed laterally with respect to the vertical extent of the channels, the angles of said extensions being alternately in opposite directions for the several shoes.

15. In combination with the discharge spouts of a plurality of grain elevator legs, a grain distributor comprising a framework forming a corresponding plurality of parallel vertical channels into which said discharge spouts respectively project, a multiplicity of spout shoes extending across and above one another along all said channels, and a vertical chute slide in each channel having an open side through which said discharge spouts respectively project, each of said chute slides having a bottom adapted to cooperate with any selected one of said spout shoes to control the flow of grain from the discharge spout through the chute slide to go to said selected spout shoe, whereby grain may simultaneously be delivered from all said discharge spouts into a single spout shoe or from each of said discharge spouts into a separate spout shoe.

16. In combination with a discharge spout of a grain elevator leg, a grain distributor comprising a framework forming a vertical channel having the discharge of the discharge spout across the top thereof, a vertical chute slide in the channel having an open side adapted to straddle with its

edges the discharge spout, a roller pulley journaled in said frame adjacent the discharge part of the discharge spout, and a belt running over said roller pulley attached to the lower end of the chute slide and operating to close the open side of the chute slide below the discharge spout and forming means to lift the discharge spout vertically into any desired position.

17. A grain distributor embodying a vertical channel and a multiplicity of spout shoes opening above one another across the opposite sides thereof, a chute slide movable vertically in said channel, said chute slide being cut-away at its bottom opposite the spout shoe openings, a bottom member pivoted between said cut-away portions, and means to swing the bottom member into either of two sloping positions, whereby it will guide grain moved through the chute slide to pass through said cut-away portion to enter a selected one of a spout shoe on either side of the channel.

18. A grain distributor embodying a vertical channel and a multiplicity of spout shoes opening above one another across the opposite sides thereof, a chute slide movable vertically in said channel, said chute slide having its ends at the bottom cut out in the form of a V and having sides adjacent the spout shoe openings terminating in substantially the horizontal plane of the apex of the said cut out V's so as to leave in effect cut-away portions, and a bottom member pivoted at the apex of said V portions, and means to swing the bottom member to close the bottom of the chute slide in either of two sloping positions whereby it will guide grain moving through the chute slide to pass through said cut-away portion to enter a selected one of the spout shoes on either side of the channel.

19. In a grain distributor a multiplicity of spout shoes having adjacent openings, vertically disposed, and a chute slide for receiving grain from the discharge spout of an elevator leg and guiding it into any selected one of said spout shoe openings, said chute slide having its ends at the bottom cut out in the form of a V and having its sides adjacent the spout shoe openings terminating in substantially the horizontal plane of the apex of said cut out V's, so as to leave in effect cut-away portions and resulting openings turned toward the spout shoe openings, a bottom member pivoted at the apex of said V portions, means to swing the bottom member to close the bottom of the chute slide in either of two sloping positions for guiding grain delivered through the chute slide to the selected one of the spout shoe openings, and means on the edges of the pivoted bottom member to seal the same upon one set or the other set of the edges of said V's.

20. In a grain distributor, means forming a vertical channel and a second vertical chute-like channel adjacent the same, a series of spout shoes having laterally extended openings to the vertical channel along a side adjacent the second channel and adapted to feed grain to the elevator storage bins, a chute slide movable vertically in the first-named channel and having means adapting it to be united for delivery of grain to any selected one of said spout shoes, and a self-closing door in the chute slide adapted to open to permit discharge of grain through the chute-like channel when for any reason the system becomes clogged.

ROY I. PATTERSON.
